Primary Examiner — Robin V Webster*(74) Attorney, Agent, or Firm* — Aleksander Medved(57) **CLAIM**

The ornamental design for a shaker core, as shown and described.

DESCRIPTION

FIG. 1 is a perspective view of a new design for a shaker core.

FIG. 2 is a front view thereof;

FIG. 3 is a rear view thereof;

FIG. 4 is a top view thereof; and,

FIG. 5 is a bottom view thereof.

The broken line showing of portions of the shaker core is included for the purpose of illustrating and forms no part of the claimed design.

1 Claim, 2 Drawing Sheets(56)
